KARL SCHUMANN, OF POTSDAM, GERMANY, ASSIGNOR TO SIEMENS-SCHUCKERTWERKE AKTIENGESELLSCHAFT, OF BERLIN-SIEMENSSTADT, GERMANY, A CORPORATION OF GERMANY

CORES FOR CABLES FOR COMMUNICATION CIRCUITS

Application filed November 25, 1930, Serial No. 498,017, and in Germany November 23, 1929.

I have filed an application in Germany, November 23, 1929.

My invention relates to a method for manufacturing cores for cables for communication circuits.

In manufacturing cables for communication circuits it is, as is well known, difficult to obtain for pairs as well as for stranding elements of higher order, uniform values of 10 capacitance and therewith differences of capacitances as uniform as possible. It has been found that after the stranding of the cable, particularly the operating capacitances vary quite non-uniformly. These 15 unequal changes in the capacitance are apparently not only caused by the manner in which the twisting or stranding is performed but depend to a great extent upon the diameter of the insulated cores and upon the 20 alteration in the diameter occurring during the twisting or stranding. To obtain equal capacitances it has already been proposed to use for building up the cores and as spacing means, insulating paper of as 25 uniform thickness as possible and of uniform dielectric constants, and paper string having as much as possible uniform thickness and being wound in each case with the same pitch. The result obtained was, however, surprising in that after the cabling of 30 even such uniform material, some stranding elements would show values of capacitance, quite different from the remainder of the stranding elements.

According to my invention, this drawback is avoided by laying the paper cording on the cores not with a completely uniform pitch, as was hitherto painstakingly done but, on the contrary, with a pitch as irregular as possible. It was found that the change in the diameter of individual insulated cores and therewith the change in the values of their capacitance was principally caused by the paper cord of one core pressing 45 itself into the paper cover of the neighbouring core at the places where the paper covering is not supported by the cording of the cores.

In the accompanying drawing, illustrating 50 my invention, Figs. 1 to 5 show different

modes of winding the paper cord onto adjacent cable cores.

The application of the paper cord may be carried out as shown for example in Fig. 1, by winding the cord with a completely irregular pitch; or the pitch may be periodically altered as in Fig. 2, for instance in such a manner that over 10 cm. length of the core the pitch of the cord windings is about 5 mm., and over the next 10 cm. core 60 length the pitch is about 10 mm. The pitch may also be increased gradually to a certain limit and then decreased again gradually, as shown in Fig. 3. It is also possible, as shown in Fig. 5, to wind on one core, two 65 cords running parallel at, for instance, a distance of 7 mm., for example with a total pitch of 14 mm., and on another core only one cord with a pitch of 7 mm. In this case the cores with two cords have about 50% 70 more paper, but as shown by experience this greater quantity of paper is of no great consequence for the value of the capacitance. In some cases the capacitance can be equalized by making the diameter of the cores 75 with two cords larger than that of the cores with one cord, for example, by passing the cores with two cords through a somewhat wider shaping die than the cores with one cord. In quads, it is advantageous to arrange these cores so that the cores with one cord form one pair and those with two cords the other pair of the quad.

It is also possible to wind the cords onto the cores of one pair of a quad, for example, with a pitch of 7 mm., and to give to the cord windings of the other pair a pitch of 8 mm., so that it is impossible for neighbouring cores to press themselves into one another for any appreciable length. Here 85 again, the greater quantity of paper cord required for the core having the smaller pitch may be compensated by making the diameter of these cores somewhat larger. When cores with cord windings arranged 90 in this manner are laid next to one another, it is impossible for one of the cores to be pressed into the other for any appreciable length, but all the cores will, when compressed, press themselves reciprocally into 95 100

one another to about the same extent over a cable section of approximately the same length, so that although the capacitances will increase to a certain degree, there will be no relative inequality in the values of the capacitances.

I claim as my invention:

1. A telephone cable having a plurality of insulated strands, each strand consisting of a core conductor, paper cord wound upon said conductor and paper tape spirally wound over the cord winding, adjacently located cord winding turns of adjacent cable strands having the same winding direction but different total pitch.

2. A telephone cable having a plurality of insulated strands, each strand consisting of a core conductor, paper cord wound upon said conductor and paper tape spirally wound over the cord winding, adjacently located cord winding turns of adjacent cable strands having the same winding direction but different pitch, at least one of two adjacent strands having its cord winding laid with successive turns of unequal pitch.

3. A telephone cable having a plurality of insulated strands, each strand consisting of a core conductor, paper cord wound upon said conductor and paper tape spirally wound over the cord winding, adjacently located cord winding turns of adjacent cable strands having the same winding direction but different pitch, at least one of two adjacent strands having its cord winding laid with entirely irregular pitch.

4. A telephone cable having a plurality of insulated strands, each strand consisting of a core conductor, paper cord wound upon said conductor and paper tape spirally wound over the cord winding, adjacently located cord winding turns of adjacent cable strands having the same winding direction but different pitch, at least one of two adjacent strands having its cord winding laid with periodically varying pitch.

5. A telephone cable having a plurality of insulated strands, each strand consisting of a core conductor, paper cord wound upon said conductor and paper tape spirally wound over the cord winding, adjacently located cord winding turns of adjacent cable strands having the same winding direction but different pitch, at least one of two adjacent strands having its cord winding laid with varying pitch between adjacent turns, which gradually varies over the length of the strand from a minimum pitch at least once to a maximum and back to a minimum.

6. A telephone cable having a plurality of insulated strands, each strand consisting of a core conductor, paper cord wound upon said conductor and paper tape spirally wound over the cord winding, adjacently located cord winding turns of adjacent cable strands having the same winding direction

but different total pitch, one of the adjacent strands having its cord winding laid in two spaced parallel spirals, the other adjacent strand having one spaced spiral cord winding.

In testimony whereof I affix my signature.

KARL SCHUMANN.
